LIGHTED PUSH BUTTON SWITCH ASSEMBLY
John O. Roeser, Park Ridge, Ill., assignor to Illinois Tool
Works Inc., a corporation of Delaware
Filed Jan. 10, 1961, Ser. No. 81,862
24 Claims. (Cl. 200—167)

This invention relates in general to push button switch assemblies and more particularly relates to a lighted push button switch assembly wherein the push button unit and lamp holder unit are detachably mounted and may be quickly and easily removed to facilitate bulb replacement.

In the electronic control field, there has long existed a problem of obtaining a compact, highly reliable, precision, lighted push button switch unit. In certain types of equipment, such as control consoles, it is often necessary to employ a plurality of circuit controllers, such as push buttons. It is preferable that each of these push buttons be mounted in a manner such that the button is normally flush with the surface of the panel. It is often required that these circuit controllers or push buttons be constructed to provide visual indications of the different conditions of the control circuit, such as condition A, condition B, and condition C. This can be conveniently accomplished by means of lamps located beneath the operating surfaces of the push buttons. Since the control consoles with the push buttons mounted therein are often bathed in ambient light either from natural sources or artificial sources, it is important that the condition of the circuit is readily visible to the eye under these ambient conditions. Further, since the lamps employed in these units have a relatively short life, substantially less than that of the rest of the components, it is desirable to have them arranged such that the failure of a single lamp will not render useless the push button unit during a control operation. At the same time, failure of a lamp should be readily ascertainable and the construction of the unit should permit its ready removal and replacement. For example, during a control operation, if a lamp should fail, it is often desired that the switch button be so arranged that the condition of the circuit is still indicated by the push button so that the operation being controlled does not have to be stopped for the mere failure of a single lamp in a control circuit. Yet, immediately after the control operation, the lamp may be readily replaced, the fact of its being defective being readily ascertained from the visual inspection of the push button unit.

Accordingly, it is an object of this invention to provide an improved circuit controller.

It is also an object of this invention to provide a circuit control device with improved means therein for separately indicating different conditions of a controlled circuit.

Another object of the invention is to provide a circuit controller of the push button type having therein a plurality of indicating lamps beneath the operating surface of the push button which are mounted in such a manner as to permit their quick removal and replacement.

It is a further object of this invention to provide an improved circuit controlling device which is of a high precision nature, is compact in all three dimensions, of rugged construction and providing high reliability.

It is a further object of this invention to provide an illuminated push button unit utilizing a novel lamp light directing means there preferably being four lamps in the unit and whereby a single lamp of the plurality of lamps will light up at least eighty percent (80%) of the indicating surface of the push button unit.

It is a further object of this invention to provide a lighted push button unit where in certain forms there is no leakage of light around the side edges of the unit to confuse the observer as to the condition being indicated.

A further object of this invention is to provide an assem-

2

bly having an outer casing with a latch means, the push button unit and lamp holder unit being quickly and easily removed from latched engagement with the casing for replacement of lamps.

Another object of the invention is to provide a lamp holder unit and push button unit which are relatively moveable to each other in the casing such that in normal operation, the lamp unit is not subjected to the actuating force on the push button unit so as to increase the useful life of the rather delicate lamps disposed in the lamp holder unit.

Another object of this invention is to provide a terminal block means having spring contacts therein which provide positive contacts over a wide range of tolerances, are compact, and have a heavy current carrying ability commensurate with other components in the circuit.

It is a further object of this invention to provide a lighted push button unit which normally utilizes four lamps each of which is adapted to light up eighty percent (80%) of the indicating surface which may be quickly and easily converted to a unit wherein each individual lamp will light up only twenty-five percent (25%) of the surface to provide more separate indicating functions if desired.

It is a further object of this invention to provide a high precision alternating unit wherein ratchet means is employed to convert high precision switches which normally open a circuit on an actuation stroke and close the circuit upon release of the actuation pressure to a switch unit which opens upon an actuation movement and does not close that circuit until the downstroke of the next actuation.

Still another object of this invention is to provide a high precision ratchet mechanism which utilizes a positive pawl means coacting with a non-spring loaded combination ratchet gear and cam means, the cam means cooperating with a lever mechanism which has a single positive actuated position, and an either/or final position is obtained. This is obtained even though the operator of the push button unit varies the force of actuation and/or in the event of mechanical deviation from a full stroke.

Another object of this invention is to provide an assembly as above described which is well adapted for mass manufacturing techniques, is easy to assemble and maintain, is pleasing in appearance, has a long field life, and is otherwise well adapted for the purpose for which it was designed.

The novel features that are characteristic of the invention are set forth with particularity in the appended claims. An understanding of the invention both as to its organization and its mode of operation, together with additional objects and advantages thereof, will be best understood by reading the following description in conjunction with the accompanying drawings, wherein:

FIGURE 1 is an exploded perspective view of part of the components making up the novel assembly, the right-hand portion of the components shown on the first sheet of drawings being assembled below the components shown in the left-hand portion of the sheet as indicated by the long arrow therebetween;

FIGURE 2 is a continuation of the exploded perspective view of FIGURE 1, the parts along the left-hand side of the sheet fitting in the final assembly in the bottom of the components shown on right-hand side of FIGURE 1 as shown in FIGURE 5;

FIGURE 3 is a plan view of the component shown in the upper right-hand corner of FIGURE 1;

FIGURE 4 is a sectional view along lines 4—4 of FIGURE 3;

FIGURE 5 is a sectional view taken along lines 5—5 of FIGURE 3, said sectional view being taken after assembly of most all of the components;

FIGURE 6 is a bottom plan view of the terminal block means shown in the lower left-hand corner of FIGURE 2;

FIGURE 7 is an exploded perspective view of four of the major sub-components of the switch button assembly;

FIGURE 8 is an end view of the precision ratchet assembly in association with the switch means as shown in the upper right-hand corner of FIGURE 2, the view being taken from the reverse side of that shown in FIGURE 2; and

FIGURE 9 is a sectional view along lines 9—9 of FIGURE 8.

Before discussing the detailed construction of the lighted push button assembly 10, it would appear best to review FIGURE 7 which shows most of the major components of the invention. As shown, an outer casing 14 is associated with a terminal block means 16. A high precision ratchet mechanism 18 which is shown in FIGURES 8 and 9 fits within the terminal block means 16. The ratchet mechanism is in turn associated with a high precision switch means 20. A unitary push button and lamp holder unit 12 is adapted to fit in the top portion of casing 14.

As shown in FIGURE 5, the lighted push button assembly 10 is adapted to be mounted to a panel 22 having an upper surface 24 and an aperture 26 formed therein. The casing unit 14 is adapted to fit within an aperture 24, shown with a square configuration having sidewalls 28. The casing 14 is essentially tubular and formed to provide a square annulus. Its upper end 30 is adapted to be mounted flush with surface 24 of the complementary panel on which it is adapted to be mounted. The sidewalls 28 of the casing 14 are provided with a pair of oppositely disposed angular mounting flange brackets 34 and 36 which are fixed to the sidewalls 28 in any convenient manner and have holes 38 and 40 to facilitate their mounting on the panel. The upper end of the casing is notched or recessed at 42 and 44 to provide access for a tool to permit removal of a unitary push button and lamp holder assembly means 12 as shall become apparent. As shown in the lower right-hand corner of FIGURE 1, the casing 14 is formed with a pair of oppositely disposed windows 46 and 48 on opposite sides of the casing. A spring member 50 having a detent portion 52 is associated with window 48 and a like spring member 54 with detent portion 56 is associated with window 46, the springs 50 and 54 being suitably mounted, as by pin means 58 and 60.

The bottom of the casing 14 is notched out on two opposite side portions 62 and 64 so that the other two sidewalls are slightly longer (see 66 and 68). The longer sidewalls 66 and 68 are formed with central tab means 70 and 72 for coaction with the terminal block means 16, as shall be later explained. From the foregoing, it is seen that the casing essentially comprises an essentially tubular housing having angular flanges on the outer surfaces adapted to be mounted to the panel, there being latch means on the interior thereof, and having an irregular bottom surface which, as shall be described, is adapted to key the terminal block means 16 to orient it with the casing.

The terminal block means 16 is shown as an assembled sub-component in the lower right-hand portion of FIGURE 7 and essentially comprises a base portion 74 which is preferably formed of insulating material such as a thermo-setting plastic. Because of its irregular configuration, it is preferred that the base member 74 be of molded construction as for example from "nylon." As shown in the lower portion of FIGURE 2, the top surface 75 of the terminal block base member 74 is provided with narrow shoulders 76 and 78, defined by short upstanding lugs and ridges 80 and 82 which are offset inwardly from the side surfaces of member 74 and are oppositely disposed. A pair of shoulders 84 and

86 which are downwardly offset from surface 75 are formed in the other two side edges at right angles to shoulders 76 and 78, said shoulders 84 and 86 being interrupted approximately at their mid-portion to provide oppositely disposed tab receiving recesses 88 and 90.

The base 74 is preferably formed with a rectilinear depending lug 92 which is centrally located. The lug 92 is formed with a central threaded bore for receipt of the precision ratchet means 18 to be described. The top surface of the base member 74 is formed with four symmetrically arranged depressions or wells 96a, 96b, 96c, and 96d. As shown in FIGURE 6, each of the wells or depressions 96a-d are formed with a rectilinear bore or passageway 98a-98d for receipt of a depending portion of the terminal means as shall be later described. On the bottom surface of the base member 74, and adjacent to the through rectilinear bores 98a-98d are recesses or slots 100a-100d which are adapted to provide access to terminals disposed in slots 98a-98d, as well as providing an abutting surface for a retaining tab on the terminals.

A pair of through bores 102 and 104 are respectively formed in base member 74 intermediate the terminal receiving depressions or wells 96b and 96c, and 98a and 98d respectively. The bores 102 and 104 are adapted to receive the common terminal means 126a-b, as shall be later described. They are provided with counterbores 106 and 108 which define shoulders 106 and 108 in the interior of the base.

The terminal block means 16 further includes electrical terminal means for the lamps which are of two part construction, and include the base unit 110a-110d and the spring portion 120a-120d. The terminal base 110a is adapted to fit into the well or depression 96a and is formed with a generally flat portion 112a which has a complementary configuration to the base of the well 96a. Three upstanding tab portions 114a extends upwardly from the base portion 112a and two depending tab portions 116a and 118a are angularly configured to extend through the slot 98a. The longer tab 118a serves as a terminal post and the shorter tab 116a is bent in an angular manner so as to engage the base portion of the recess 100a to retain the terminal 110a within the well 96a. It will be apparent that while I have described only terminal 110a, that there are four symmetrically arranged terminals 110a-110d and each of them is mounted in the respective wells 96a through 96d, in the same fashion terminal 110a is mounted in well 96a.

The upstanding tabs 114 of the various terminal bases 110a-110d are adapted to engage and anchor the lower convolution of the volute springs 120a-120d. As shown in the sectional view in FIGURE 5, the springs 120a-120d are preferably of rectilinear cross section which greatly enhances their current carrying ability. The cross sectional area of the springs permits relatively heavy current carrying capacity since the area of the wire equals the current carrying cross section of other conductors in the circuit thus preventing circuit overload in the area of the springs. As will be seen, the winding of the coil in volute fashion accommodates a wide range of tolerances in the mounting of other units of the assembly. The springs 120a-120d are preferably conservatively stressed so that the amount of spring action of the spring is only that amount that is sufficient to give contact pressure to assure proper electrical characteristics without the introduction of strong biasing forces into the assembly. As can be seen in FIGURE 7, the top surface 124 of the springs 120 are spaced a considerable portion above the top surface of the terminal block base 74 when the springs are assembled in the wells 96, the springs being held in place by the tabs 114 on the terminal bases 110.

Each of the common terminal means 126a and 126b may be formed from four components. The components in assembly 126a only are described. Common terminal means 126a has a component denominated as base portion

128a which is essentially cylindrical in form having an external shoulder 130a and a central bore 134a. The base of member 128a is formed with circular shoulders or ridges 132a which provides extra soldering surface. The base 128a is adapted to be disposed in bore 104 with shoulder 130a engaging shoulder 128 and with the rigid portion 132a extending below the base member 74 of the terminal block for access for soldering to lead wires. As shown in FIGURE 7, the tubular neck portion of member 128a extends above the top surface of base member 74 and is encircled by a spring 136a. A pin or shaft 138a and a head portion 140a having a pointed tip 142a are assembled in the bore 134a, the top convolution of the spring 136a engaging a small shoulder 141a of the head 140a, and the bottom convolution of the spring 136a engaging a shoulder 131a on member 128a. The length of pin 138a, head portion 140a and the neck portion of member 128a is such that in the assembled relation, the spring is in a relaxed or non-stressed state and the assembly is held in place by the close gripping association of the upper convolution of the spring with shoulder 141a and the close gripping of the lower convolution with shoulder 131a. Thus, in assembled relation, the common terminal means may be compressed against the bias of spring 136a. In its relaxed state the spring 136a will not cause disassembly of the parts. The common terminal means 128b is assembled in aperture 102 of the base means 74 in a manner similar to the assembly of 126a in aperture 104.

After the preassembly of the terminals to the base 74, the entire terminal block assembly 16 is assembled in to the bottom portion of the casing 14. The correct orientation of the base 74 to the casing 14 is determined by the surfaces 66 and 68 engaging shoulders 84 and 86 and surfaces 62 and 64 engaging shoulders 76 and 78 of the base member 74. Tabs 70 and 72 are bent into the tab receiving recesses 88 and 90 to retain the terminal block in its assembled relation.

The push button 144 and lamp holder 146 elements are shown in assembled relation as a unit 12 at the top of FIGURE 7. The lamp holder unit 146 comprises a base member 148 which is preferably formed of molded plastic material. It is essential that the base portion 148 be made of a dielectric material. The base member 148 is formed with a plurality (4) symmetrically arranged lamp apertures 150a through 150d which have diameters suitable for receiving the casing of a bulb unit. The base member 148 is formed with a central through aperture 152 and four symmetrically arranged upwardly projecting shells 156a-156d. The shells 156a-156d are offset inwardly from the side edges of the base member 148 to define a shoulder 154 which is located approximately in the mid-portion of the axial length of the total lamp holder unit 146. The shells 156a-156d are larger than the bores 150a-150d and each have a generally rectilinear annular configuration, the tops of which have been truncated or angularly arranged relative to a horizontal plane through the axis of the bores 150a-150d. The highest point on the shells 156 through 156d (see FIGURE 4) is that point adjacent to the corner area of the base member 148. The shells 156a-156d are arranged in quadrature in top view, and as arranged, the portions of the individual shells which are spaced from the other three shells the greatest distance in the horizontal plane also project vertically the greatest distance above the base portion 148. Stated another way, the shells 156a-156d are each configured in a manner such that the top surfaces thereof slant downwardly toward the central aperture 152. Thus, points 160d and 162d, for example, are on the same elevational plane, while the lowest portion of the individual shell is that portion 164 which is curvilinear and immediately adjacent to the aperture 152. The wall portion of the shells 156a-156d (see FIGURES 3 and 4) immediately adjacent to the central aperture 152 are curvilinear

throughout their axial extent and spaced radially outwardly therefrom a short distance.

The base 148 is formed with two spring receiving apertures 172 and 174 in the intermediate web portion of the base immediately between shells 156c and 156d, and 156a and 156b respectively. The outer margins of the walls of the shells are reduced in thickness to provide an extension of the bores 172 and 174 at 170c and 170d relative to bore 174. It will be noted that bores 172 and 174 do not extend through the base. The bottom of the bores serve to provide an abutting surface for a spring 244, later discussed. Also, provided in the walls of the base portion 148 are grooves 176 and 180 which define latching shoulders 178 and 182 respectively on the side edges of the base. Immediately below the respective grooves 176 and 180 are cam surfaces 179 and 181 respectively which coact with the rounded surfaces 56 and 52 of the spring means 54 and 50 mounted on the casing 14.

The bottom of the base portion 148 is formed with spaced tab receiving bores 184 and 186 for receipt of a tab from the fixedly mounted common terminal connectors 188a and 188b. The members 188a and 188b are shown in FIGURE 1 immediately below the base 148 and each comprise a central flat portion 190 having a central locking tab 194 and two somewhat longer flared springy tabs 192 and 196. As shown in the sectional view of FIGURE 5, the locking tab 194b of member 188b is adapted to fit within bore 186, the two angular tabs 192b and 196b respectively extending upwardly along the side-walls of bores 150b and 150c for engagement with the sidewalls of lamps disposed within said bores. Member 188a is similarly disposed so that tab 194a fits into bore 184 and the two springy side tabs 192a and 196a fit within bores 150a and 150d. Thus, members 188a and 188b serve the dual function of providing a fixed common terminal connector means for the lamp casing as well as providing a light springy action against a lamp unit disposed within the lamp holder bores to adjust for slight tolerance differences in the lamp holder and lamp units per se.

The four lamps 198a through 198d are available commercially. Each has a metallic sidewall 200a-200d, a radially outwardly extending shoulder 202a-202d and a light transmitting glass head portion 204a-204d. The respective lamps 198a-198d fit within the respective bores 150a-150d with the shoulders 202a-202d abutting the bottom surface of the base member 148. The terminal tabs, such as 192a-b and 196a-b help to retain the bulbs in mounted position, yet permitting easy removal thereof.

As briefly mentioned heretofore, there are many applications where it is extremely desirable to have the light from a single lamp of the four lamps in a unit of the type previously described, project upwardly to light up at least eighty percent (80%) of the total indicating surface and two lamps light up all of the indicating surface. One arrangement of lamps that is quite common is to electrically connect the four lamps in such a manner that a single pair of lamps are lit simultaneously and the other remaining pair of lamps are lit at a different time. The shell covers 206a-d are preferably made of pellucid material, i.e., either transparent or translucid, colored or clear depending on characteristics desired. For indicating purposes, it is often found desirable to color code by using colored filter means. One common color code is red and green, and to this end colored shell covers 206 may be mounted on the tops of the respective shells 156a through 156d. For illustration purposes, the arrangement of light and colors herein discussed will allude to shell covers 206a and 126c that are green and shell covers 206b and 206d that are red. The respective lamps associated with the red filters will be discussed as though they form a pair which are lighted simultaneously, and the green pair will light up simultaneously as well, although many other arrangements and colors are available. This arrangement is found to give good indicating character-

istics on the indicating surface. The shells 156a-156d are larger than the bulb unit and the interiors thereof preferably are treated, coated, or of a material which will provide a highly reflective surface with diffusing characteristics.

It has been found important to avoid illumination "hot spots" or concentrations of light on an indicating surface above the lamp holder unit and it is desired to have an even pattern of light on the indicating surface. By the angularity of the top surface of the individual shells 156a-d, the reflective nature of the internal surface of the shells, the refractive index of the filter material, and the location of the lamp center within the shells (as shown), it is possible to direct the light from an individual lamp in a manner which will produce no "hot spots" on the indicating surface, and additionally to light adequately eighty percent (80%) of the total indicating surface using a single bulb. In directing the light from a single bulb, the corner area on the indicating surface opposite from the location of the bulb is hardest to light. However, when two properly arranged bulbs are simultaneously lighted, the entire indicating surface is illuminated in an even pattern, the intensity with two bulbs being noticeable over an indicating surface illuminated with only one bulb. Also, the angularity of the shells, sidewalls, margins and the filter covers 206a-d greatly aid in lighting the opposite corners of the indicating surface.

The push button unit 144 which coacts with the lamp holder unit and other elements of the total assembly is comprised of a hollow rectilinear tubular member 208 which is open at both ends. Spaced a short way from the top surface of member 208 and on opposed sides are two windows 210 and 212, each of which provide a tool receiving surface 211 when the push button unit is mounted within the casing, the windows 210 and 212 being aligned with recesses 42 and 44 of the casing (see FIGURE 7). While the tool receiving recesses 210 and 212 are shown in form of a window, in those applications where it is absolutely necessary that there be no leakage of light around the outer margins of the housing 208, the windows 210 and 212 may be formed in the shape of a dimple in the metal so as to provide a continuous surface preventing any leakage of light.

Fixedly mounted in the vicinity of the bottom portion of the housing 208 are four vane members 214a through 214d with a centrally mounted hub member 216. The hub member 216 is formed with a necked down shank portion 218 which depends from the hub 216, the necked portion at its juncture with the hub defining a shoulder 220. The interior of the hub and the shank portion has a central bore 222, also having an enlarged bore section 224 located at its upper end which defines an intermediate interior shoulder 226. The top surface of the hub projects slightly above the top surface of the thin vanes or spider member 214 (see FIGURES 1 and 5), and is normally notched at 228a through 228d in alignment with the vane members 214.

Mounted in the hub bore of the housing 208 is a pin member 230 having an enlarged head 232 adjacent the top end thereof and a groove 234 adjacent its lower end. A washer 236 is placed over the end of the pin 230 and a suitable retainer ring 238 is disposed in the groove 234 at the end of the pin (see FIGURE 5). On the exterior of the hub shank 218 there is mounted a heavy force transmitting spring member 240 which engages shoulder 220 at its one end, and with its other end engages the lower surface of the washer 236. As seen in FIGURE 5, the washer should be of sufficient diameter so that when the push button unit 144 is assembled to the lamp holder unit 146, the washer 236 will also engage the bottom surface of base member 148 which surrounds the central bore 152 to maintain an assembled relationship between the push button unit 144 and the lamp holder unit 146. Relatively weak springs, in coil form, such as 242 and 244 are disposed in the bores 172 and 174 so that they engage the

bottom of the bores and vanes 214c and 214a to bias the push button unit 144 away from the lamp holder unit 146 to the position shown in FIGURES 5 and 7.

A translucent cover 246 may be mounted on the margins 5 of the upper surface of the push button housing 208. This top surface serves the dual function of an actuating surface for the push button, as well as being the indicating surface which is lighted by lamps disposed in the lamp holder unit. As shown in FIGURE 5, the top surface 10 248 of the push button unit is preferably made to be flush with the panel surface 24 and the upper surface 30 of the casing 14. In installations where it is desirable that the indicating surface 246 project above the panel surface, the casing windows 210 and 212 are formed as dimples, 15 rather than as windows. This prevents light leaking through a perforated side wall, and yet provides adequate means for dismounting the combination push button lamp holder means 12.

In some applications, it is desirable that each of the 20 lamp filters 206a-206d be of a different color. With such an arrangement, five indicating functions may be provided by the push button unit, i.e., four separate colors plus the control function of no light showing. When this is desired, 25 relatively large rigid vanes 250 and 252 having crossed notches 254 and 256 may be preassembled into the push button unit prior to the fixing of the top surface member 246. The vanes 254-256 are conveniently placed in the slots 228a-228d which orients them in their desired relationship to the rest of the assembly.

The push button and lamp holder assembly 12 is designed for easy removability as a unit, but once assembled in place within the casing 14, the push button unit 144 has relative movement to the lamp holder unit 146. To assemble the unitary push button and lamp holder assembly 35 within the casing, the components are arranged as shown in FIGURE 7. The entire unit 12 is pushed downwardly relative to the casing so that cam surfaces 179 and 181 on the lamp holder base 148 push the detent portions 56 and 52 of the latching means on opposite sides of the casing 14 outwardly from each other. On further downward movement of unit 12, the portions 56 and 52 will 40 then engage shoulders 178 and 182 on the base of the lamp holder means 146. The latching means on the casing thus provides, due to the configuration of the base 146 and of the springs 50 and 54 an "easy on" "hard off" 45 latching relationship.

As it is important that the lamp holder unit 146 not be disturbed or moved every time there is an actuation of the push button unit 144, certain relationships which permit this should be noted. For example, the spring 240 is 50 much heavier and stronger than the combination of forces supplied by the springs 242 and 244. Thus, an actuating force (downwardly) on the push button unit 144 will cause downward movement of pin 230, the force transmitting structure being the sidewalls of the housing 208, the spiders 214a-d, the stem shoulder 220, the spring 240, the washer 236, the retaining ring 238, and the pin 230. The springs 242 and 244 merely serve to return the push button unit 144 to its relatively separated position to the lamp holder unit 146 after release of the actuating force. Further, the relatively heavy spring 240 permits over travel of the push button unit 144 to provide the desired latching cooperation needed for initial installation of the lamp holder unit 146 with the spring detents in the casing. Thus, in 55 initial assembly of the unit 12 in the casing, spring 240 allows the push button unit to be moved against the relatively weak force of springs 242 and 244 until there is a solid force transmitting connection between the housing 208 and the shoulders 154 on the lamp holder unit which in turn will transmit sufficient force to deflect outwardly the springs 50 and 54. Spring 240 also provides for overtravel of the push button unit in the event that a heavy force is supplied to the bottom of pin 230 by the top of an actuated member. Thus, there will be relative movement of the pin 230 relative to the hub 216 before

the lamp holder means 146 is engaged by the push button unit 144 thereby preventing disturbance of the lamp holder means once it is latched in place.

Once the unitary lamp holder and push button unit means 12 is latched in place within the interior of the casing 14 which already has the terminal block means 16 mounted in the bottom thereof, it will be seen that the volute springs 120a-d engage the bases of their respective lamps and the heads 142a-142b of the spring loaded common terminals 126a-b engage the bases of the common terminal contractors 188a and 188b respectively. With the form of terminal block construction shown, there is ready access at the bottom for making solder connections to other parts of the electrical circuitry. Also, a wide variation of dimensional tolerances is permitted between the lamp holder means 146 and the terminal block means 16 due to the spring nature of the contacts. The nature of the springlike contacts is such that electrical continuity is provided even when the unit 10 is subjected to vibration.

The precision ratchet means 18 and switch means 20 are mounted in the base of the terminal block means in the central aperture 94. An inverted U-shaped bracket member 258 is formed with a bail portion 260 and depending legs 262 and 264. The bail portion 260 is formed with a central aperture 266, the margin being upset to provide a small orienting and locking tab 268. An actuating means force transmitting unit 270 for the ratchet means 18 includes a rod or pin 292 and a tubular member 272 which is threaded on its outer diameter, as at 274, and is provided with a central bore 275. The tubular member 272 is formed with a radially extending shoulder 276 and an elongated axially aligned slot 278 on the upper threaded portion. As shown in FIGURE 9, locking tab 268 fits into the base of the slot 278 to retain the tubular member 272 in the aperture 266.

The lower extremity of the tubular member 272 is preferably crimped or spun over to retain member 308. A second slot 282 is formed in that portion of the tubular member which is disposed within the U-shaped housing 258, said slot 282 being oppositely disposed from slot 278, as well as being aligned with the axis of the tubular member. A counter bore 286 together with bore 275 and the tubular member 272 define an internal shoulder 290. Also, it will be noted that the upper end of bore 275 is chamfered at 288.

The pin 292 fits within the tubular member 272 and is formed with a shoulder 296 which coacts with internal shoulder 290 to limit upward movement thereof. The lower portion of pin 292 is bifurcated by a slot 298 and carries a cross pin 300 which serves as a pivot for a pawl member 302 having a tooth portion 304 which extends through slot 282 in tubular member 272. A coil spring 306 is interposed between the lower end of pin 292 and a spring stop member 308 which as aforementioned is mounted by the crimped ends 280 on the tubular member 272. Member 308 is formed with a short upstanding lug portion 310 which serves as a spring guide for coil spring 306. The position shown in FIGURE 9 is that of the non-actuated position. Movement of pin 292 by engagement with top surface 294 will cause movement of the pawl along the slot 282 against the bias of return spring 306. The configuration of the pawl 302 is such that it can not have further clockwise movement from the position shown in FIGURE 9, only a counterclockwise movement.

Before discussing the rest of the ratchet mechanism, perhaps it will be desirable to explain the precision switches which are shown in semi-diagrammatic manner. The precision switch means 20 essentially comprises two such switches 312a and 312b which are mounted in side by side relation between the legs 262 and 264 of the bracket at the lower extremity thereof. Each switch has a housing 314. Only switch 312a will be described for brevity.

The switch unit 312a includes a housing 314a made of insulating material having therein fixed contact means

316a, 318a in spaced relation and a common contact 320a disposed on the other side of the switch. The fixed contacts 316a, 318a and 320a are connected to depending terminal members 324a, 326a and 328a respectively. A plastic base member 330a is formed with a central depression 331a. The housing 314a is apertured above the depression 331a in the base to mount an actuator button 332a with a depending portion 334a which is also aligned with the central depression 331a. A spring unit 336a is mounted in the depression 331a and engages the portion 334a to bias the push button upwardly. A movable contact carrying member 338a carrying contact member 332a on the free end thereof has an over center snap arrangement by its mounting on the portion 334a and connection with spring 339a which extends through an aperture in the portion 334a. The spring 339a also engages a similarly arranged contact carrying member carrying contact member 342a which is biased to a fixed position by a spring 340a. Thus, movement of the actuator button 332a causes movement only of contact 322a to positions in engagement with either fixed contact 316a or 318a. As shown in FIGURE 9, the push button is in its depressed position and contact 322a engages contact 316a thereby completing a circuit between depending terminals 328a and 324a. Release of the actuator button, to obtain the position shown in dotted lines, will cause contact 322a to move into engagement with contact 318a thereby completing a circuit between terminal 328a and 326a.

The two switches 312a and 312b are mounted onto the bracket member 260 by two through pins 344 and 346 which extends through the respective bases 330a and 330b to fix the switches into position.

A lever actuator member 348 is formed with a pair of short upstanding arm portions 352 and 354 and is pivotally mounted at one end on a pin 350. The lever 348 is formed with a blanked out notch portion 356 on the end remote from the pivotal end, said notch 356 defining a pair of arms 358 and 360 each of which are adapted to engage the tops of the push button units. Arm 358 engages push button unit 332a and arm 360 engages push button unit 332b.

The ends of each of the arms 358 and 360 are formed with a V-shaped notch 362, the angular areas on either side thereof at 364 and 366 providing a ramp portion, each of which are angularly divergent relative to the other to provide a very definite point at 362 therebetween. The ramps 364 and 366 together with the V-shaped notch portion 362 coact with the cam means of the ratchet mechanism as shall now be described.

The combination ratchet gear and cam means 368 may be formed in a unitary manner and is preferably mounted on a pivotal shaft 370. Shaft 370 is mounted through the sidewalls of the bracket 258. The ratchet gear and cam means may be made from a suitable material in a unitary manner. The cam means portion 374 of the unitary ratchet gear and cam means 268 comprises a plurality of teeth 376 having pointed or sharp edges 378 which extend from an enlarged hub surface 380. It will be noted that the hub 380 has a diameter greater than the teeth 382 of the gear portion 372 of the ratchet gear.

The teeth 382 on the ratchet gear 372 project outwardly and are each formed with a trailing surface 384 and a leading surface 386 which define a sharp edge therebetween. The configuration of the teeth, and the disposition of the teeth around the periphery of the gear portion 372 is such that movement of the pawl 302 causes tooth portion 304 to engage trailing surface 384 on the ratchet gear causing rotation of the gear and the cam means 374. Thus, the position of the edge 378 of the cam means 374 is either in the position shown in full line, or alternatively in the position shown in dotted line in FIGURE 9.

The ratchet mechanism is of a precision nature. The arrangement of the parts and its configuration assures

that lever 348 is always either in the full line position or the dotted line position after the end of each actuation stroke of pin 292 independent of variations in actuating pressure, length of strokes, and mechanical tolerances encountered throughout the entire assembly. This obtains due to the ramp portions 364 and 366, together with the configuration of the teeth 376 on the cam means. They are so arranged that the teeth will return under the reaction force supplied by springs 336a and 336b of the switches so that the teeth 376 must either slide down into notch 362 or will be off the end of the lever so that the ends of the arm 358 will engage one of the hub portions 380 of the cam means. It should be noted that spring 306, associated with pin 292, serves the dual function of returning button 292 to the position shown in FIGURE 9 as well as returning pawl 302 to its position shown in FIGURE 9. This spring 306 is so captivated that it can neither be lost or bent out of adjustment. Further, it will be appreciated that the lever 348 and the cam and ratchet gear means 368 do not need separate springs, the spring biasing force supplied to this arrangement being only from the switches themselves.

To complete the assembly of the ratchet means 18 and switch means 20 with the rest of the components which make up the total assembly 10, a keyed annulus 388 having a keyed tab 392 and two retaining ears 394 and 396 is mounted on square lug portion 92 on the base of the terminal block means. The ears 394 and 396 are bent around the side edges to retain member 388 in position.

The tabs 394 and 396 are not bent into place until after tubular member 272 is mounted in the threaded aperture 94 in the base of the terminal block 74. Once the correct height adjustment of the top 294 of the button 292 is obtained relative to the base or bottom end of pin 230, the tabs are bent into position and the assembly is locked into place. Tab 392 prevents retrogressive rotation of the ratchet means and switch means by being disposed in the slot 278 on tubular member 272.

From the foregoing description, it will be seen that a compact, high precision, illuminated push button switch unit is provided in a compact modular construction. Although a specific embodiment of this device has been shown and described, it is with full awareness that many modifications thereof are possible. The invention therefore, is not to be restricted except insofar as is necessitated by the prior art and by the spirit of the appended claims.

What is claimed as the invention is:

1. A circuit controlling device comprising, a hollow casing means having open ends, terminal block means fixedly mounted in one end of the casing means and having a through opening, a push button unit mounted in the other end of the casing means and moveable relative thereto, said unit having a depending stem portion, lamp holder means located entirely within and latchably fixed to said casing means intermediate said unit and said terminal block means, switch means including actuator means for said switch means mounted in and extending through said opening in said terminal block means, and motion transmitting means associated with said push button unit stem and said actuator means of said switch means and extending through said lamp holder means and operable upon actuation of said push button unit to transmit motion to said actuator means to actuate said switch means, said motion transmitting means permitting overtravel of said push button unit without moving said lamp holder means.

2. The device set forth in claim 1 wherein said casing means is characterized as being fixedly mounted to a complementary apertured work panel, the end surface of said casing receiving said push button unit being flush mounted with the top surface of said panel, and the top surface of said push button unit being flush with said end surface of the casing means and said top panel surface when in non-actuated position.

3. The device set forth in claim 2 wherein said motion transmitting means further providing means to connect said push button unit and said lamp holder means together to afford a means for removal of said lamp holder means from latched engagement with said casing simultaneously with removal of said push button means.

4. The device set forth in claim 1 wherein said push button unit comprises a housing member of a configuration complementary to said casing means and having open ends, light transmitting closure means for said housing providing an actuating surface, and spider means located in the opposite end of said unit, said spider means performing the dual function of supporting a central hollow depending stem and providing light separating vanes for cooperation with lamps located in the lamp holder means.

5. A circuit controlling device comprising a hollow tubular casing, terminal block means fixedly mounted in one end of said tubular casing and having a central opening, a push button unit mounted in the other end of the casing and moveable relative to said casing and said terminal block means, said unit having a depending central stem portion aligned with the central opening in said terminal block, lamp holder means latchably fixed to said casing for removal through said other end of said casing and being located intermediate said push button unit and terminal block means and formed with a central opening receiving said stem portion of said push button unit, and motion transmitting means separate from and associated with the stem of said push button unit and cooperable with said lamp holder means upon actuation of said push button unit to transmit motion through the aperture in said lamp holder means to a motion receiving control means.

6. A circuit controlling device comprising, a hollow casing having open ends, terminal block means fixedly mounted in one end of the casing and having a central opening, a push button unit mounted in the other end of the casing and moveable relative thereto, said unit having a depending central stem portion aligned with said central opening in said terminal block, lamp holder means latchably fixed to said casing intermediate said push button unit and terminal block means and formed with a central opening receiving said stem portion of said push button unit, and motion transmitting means associated with said push button unit stem and cooperable with said lamp holder means and operable upon actuation of said push button unit to transmit motion through said aperture in said lamp holder means, said motion transmitting means including means for engaging said lamp holder means to remove same from latched cooperation with said casing, said casing being further characterized as having side walls formed with a pair of oppositely disposed latching spring means having a detent portion, and said lamp holder means is formed with a base portion having a pair of oppositely disposed latching shoulder for cooperation with said detent portion of the latching spring formed in the side walls thereof, said base portion being further formed with cam means immediately below said latching shoulders whereby an "easy on" "hard off" latching relationship of said lamp holder means to said casing is afforded.

7. The circuit controlling device set forth in claim 6 wherein said motion transmitting means comprises a relatively heavy spring means surroundingly disposed to said stem portion of said push button unit, a headed pin disposed within said stem portion with the shank portion extending therebeyond, and washer means mounted on said shank portion, one end of said spring being engageable with said stem portion and the other end being engageable with said washer means to thereby transmit motion of said stem in a first direction to the end of said shank portion of said pin, said washer means also engaging the margins of the central aperture in said lamp holder means to transmit motion thereto on movement of said push button unit in a second direction.

8. The device set forth in claim 6 wherein the terminal block means includes a plurality of bulb contact terminal means and a plurality of spring loaded common terminal means, said bulb contact means being in the form of a rectilinear in cross section volute spring means whereby good physical and electrical contact may be made with bulbs disposed in said lamp holder means when said lamp holder means is disposed in latched relation to said casing, said bulb contact terminal means and said common terminal means maintaining its good electrical and physical contact over a large range of dimensional variation of assembly.

9. The device set forth in claim 6 wherein said push button unit has a light receiving indicating surface of rectilinear configuration which also is the manually engageable portion of the push button unit, said lamp holder means being formed with a base portion of rectilinear configuration, said base portion being formed with a plurality of symmetrically arranged projecting shells each having a light reflecting interior surface, said shells projecting from said base portion generally in a vertical direction and toward said indicating surface of push button, each of said shells having an area dimension in a plane parallel to the plane of said indicating surface substantially less than the area of said indicating surface, each of said projecting shells having sidewalls projecting from the base portion in varying amounts to provide an inclined top surface on said sidewalls, and pellucid cover means mounted on the projecting sidewalls of said shells whereby light from a bulb disposed in one of said shells of said lamp holder means will light up said indicating surface of said push button unit.

10. The device set forth in claim 9 wherein said shells are symmetrically arranged in the corner portions of said rectilinear base portion of said lamp holder means, each of said shells sidewalls projecting their greatest distance above said base portion in the vicinity of the corner portions of said base portion and taper downwardly toward the mid-portion of said base portion whereby the direct rays of light from a bulb disposed in one of said shells, the reflected light from the interior of said shell, and the refraction index of said pellucid cover means on said shell all combine to light up a great percentage of said indicating surface of said push button in an even manner without hot spots thereon.

11. The device set forth in claim 10 wherein at least one of the pellucid covers for said shells is a colored filter.

12. A circuit controlling device comprising, a hollow casing having open ends, terminal block means fixedly mounted in one end of the casing and having a central through opening, a push button unit mounted in the other end of the casing and moveable relative thereto, said unit having a depending stem portion, lamp holder means latchingly fixed to said casing intermediate said unit and said terminal block means, switch means including actuator means mounted in and extending through said opening in said terminal block means, and motion transmitting means associated with said push button unit stem and said actuator means of said switch means and extending through said lamp holder means and operable upon actuation of said push button unit to transmit motion to said actuator means to actuate said switch means, said motion transmitting means cooperating with said switch means including said actuator means while permitting travel of said push button unit in at least a first direction without moving said lamp holder means, said actuator means of said switch means comprising pawl means, combination ratchet gear and cam means, and lever means mounted intermediate said terminal block means and said switch means, said pawl means being engaged by said motion transmitting means associated with said push button unit to engage said combination ratchet gear and cam means to in turn engage said lever means to provide alternate actuation of said switch means upon actuation of said push button unit to said lamp holder means.

13. The device set forth in claim 12 wherein said switch means including actuator means comprises an inverted U-shaped bracket housing member having a central aperture aligned with said central aperture of said terminal block means, said pawl means having a portion extending through said bracket aperture, switches having spring loaded actuator buttons mounted adjacent and between the ends of the legs of said bracket housing member, a pivotally mounted lever having a free end portion and engageable with said switch push buttons intermediate said free end portion and its pivotal mount, said free end portion of said lever being upset to provide angularly disposed ramp portions defining a notch, combination ratchet gear and cam means pivotally mounted for engagement with said free end of said lever means and with said pawl means, said ratchet gear and cam means being formed with a plurality of alternate tooth and hub portions arranged and configured to engage said free end portion in an alternate manner upon actuation of said pawl means by said push button unit to alternately depress and release said lever under the bias of said spring loaded switch push buttons.

14. The device set forth in claim 13 wherein said ratchet gear and cam means is freely rotatable on a shaft mounted on said bracket, the biasing force providing engagement of the free end of said lever therewith being solely provided by the spring loaded push buttons.

15. The device set forth in claim 14 wherein said pawl means comprises an axially slotted tubular member mounted in said central opening of the terminal block means, a pin means extending through said tubular member and extending therebeyond for engagement with the motion transmitting means of said push button unit, a pawl member mounted on said pin and extending through said slot in the tubular member for cooperation with the ratchet gear and cam means, and spring means captivated by said tubular member and biasing said pin and pawl means toward a first position.

16. The device set forth in claim 15 wherein said tubular member is threaded on its outer surface and is formed with an axial groove on the threaded portion and locking means is provided cooperable with said groove and said terminal block to lock said tubular member in position relative to said terminal block.

17. A circuit controlling device comprising, a hollow casing having open ends, terminal block means fixedly mounted in one end of the casing and having a central opening, a push button unit mounted in the other end of the casing and moveable relative thereto, said unit having a depending central stem portion aligned with said central opening in said terminal block, lamp holder means located entirely within and latchingly fixed to said casing intermediate said push button unit and terminal block means and formed with a central opening receiving said stem portion of said push button unit, motion transmitting means in the form of a heavy spring and pin means associated with said push button unit stem and cooperable with said lamp holder means and operable upon actuation of said push button unit to transmit motion through said aperture in said lamp holder means to a motion receiving means, said motion transmitting means including means for engaging said lamp holder means to remove the push button and lamp holder as a unit from latched cooperation with said casing, and spring biasing means located intermediate said lamp holder unit and said push button unit having a spring rate substantially less than the heavy spring portion of the motion transmitting means and operable to normally maintain the push button unit and lamp holder unit in spaced relation.

18. An alternate action mechanism comprising momentary switch means having spring-loaded actuator buttons biased outwardly of said switch means, combination ratchet gear and cam means rotatably mounted above said spring-loaded actuator button means, lever means

disposed intermediate said combination ratchet gear and cam means and said spring-loaded actuator button means for simultaneous co-action therewith, and means engageable with said combination ratchet gear and cam means operable to selectively cause said lever means to alternately and successively depress said spring-loaded button means and release same whereby an alternate action mechanism is provided.

19. An alternate action mechanism comprising U-shaped bracket housing member disposed in inverted position and having a central aperture, switch means disposed between the legs of said U-shaped bracket housing member and having spring-loaded actuator buttons, a pivotally mounted lever mounted on said U-shaped bracket housing member having a free end portion, said lever intermediate the ends thereof being engageable with said switch push buttons, said lever having a free end portion upset to provide an angularly disposed ramp portion defining a notch, combination ratchet gear and cam means pivotally mounted for engagement with said free end of said lever, means operable to move said combination ratchet gear and cam means about its axis, said ratchet gear and cam means being formed with a plurality of alternate tooth and hub portions arranged and configured to engage said free end portion in an alternate manner upon rotation of said ratchet gear and cam means to thereby alternately depress and release said lever under the bias of said spring-loaded switch push buttons.

20. A lighted push button mechanism comprising in combination:

- A. Outer housing means;
- B. Terminal block means fixedly mounted to the interior of said outer housing means;
- C. Unitary push button and lamp holder means removably latchingly mounted in said outer housing means, said unitary push button and lamp holder means comprising;

C1. Rectilinear lamp holder base means having at least five apertures therein and at least four of said apertures being operable to receive four lamp means therein;

C2. Shell means associated with said base means and individually surrounding each of said four apertures and projecting thereabove, said shell means being further characterized as providing a light reflective surface to reflect light from said lamp means when disposed in said aperture means;

C3. Pellucid cover means for each of said shell means and mounted thereon;

C4. Rectilinear push button housing means telescopingly mounted to said lamp holder base means for relative movement thereto and to said outer housing means when said push button and lamp holder means is latched in said outer means, said push button housing means having an upper screen surface and depending side walls;

C5. Means associated with said side walls of said push button housing means spaced from said screen surface, for operable association with means for transmitting motion through the fifth aperture in said lamp holder means;

C6. Said means associated with said side walls for operable association with said means for transmitting motion having an at-rest position and being movable between said shell means upon actuation of said push button housing means, and further characterized when in its at-rest position as being configured, arranged and disposed so as not to interfere substantially with light projected from lamps in any one individual shell means through the individual pellucid cover means onto said screen means;

D. Whereby light emanating from said individual lamps located in said individual shells in said lamp holder means may be projected to an appreciable portion of said upper screen on said push button means.

5 21. A lighted push button mechanism comprising in combination:

- A. Outer housing means;
- B. Terminal block means fixedly mounted to the interior of said outer housing means;
- C. Unitary push button and lamp holder means removably latchingly mounted in said outer housing means, said unitary push button and lamp holder means comprising:

C1. Lamp holder base means having a plurality of apertures therein and at least some of said apertures being operable to receive lamp means therein;

C2. Shell means associated with said base means and individually surrounding each of said some apertures receiving said lamp means and projecting thereabove, said shell means being further characterized as providing a light reflective surface to reflect light from said lamp means when disposed in said some aperture means;

C3. Pellucid cover means for each of said shell means and mounted thereon;

C4. Push button housing means telescopingly mounted to said lamp holder base means for relative movement thereto and to said outer housing means when said push button and lamp holder means is latched in said outer housing means, said push button housing means having an upper screen surface and depending side walls;

C5. Means associated with said side walls of said push button housing means spaced from said screen surface for operable association with means for transmitting motion past said lamp holder means;

C6. Said means associated with said side walls for operable association with said means for transmitting motion having an at-rest position and being movable upon actuation of said push button housing means, and further characterized when in its at-rest position being configured, arranged and disposed so as not to interfere substantially with light projected from lamps in any one individual shell means through the individual pellucid cover means onto said screen means.

D. Whereby light emanating from said individual lamps located in said individual shells in said lamp holder means may be projected to an appreciable portion of said upper screen on said push button means.

55 22. A lighted push button mechanism comprising in combination:

- A. Outer housing means;
- B. Terminal block means fixedly mounted to the interior of said outer housing means;
- C. Alternate action mechanism mounted below and to said terminal block means;
- D. Switch means mounted below said alternate action mechanism for actuation thereby;
- E. Unitary push button and lamp holder means removably latchingly mounted in said outer housing means, said unitary push button and lamp holder means being operable to actuate said alternate action mechanism to in turn actuate said switch means and comprising:

E1. Lamp holder base means having at least five apertures therein and at least four of said apertures being operable to receive four lamp means therein;

E2. Shell means associated with said base means and individually surrounding each of said four

- apertures and projecting thereabove, said shell means being further characterized as providing a light reflective surface to reflect light from said lamp means when disposed in said aperture means;
- E3. Pellucid cover means for each of said shell means and mounted thereon;
- E4. Push button housing means telescopingly mounted to said lamp holder base means for relative movement thereto and to said outer housing means when said push button and lamp holder means is latched in said outer housing means, said push button housing means having an upper screen surface and depending side walls;
- E5. Means associated with said side walls of said push button housing means spaced from said screen surface, for operable association with means for transmitting motion through the fifth aperture in said lamp holder means to said alternate action mechanism;
- E6. Said means associated with said side walls for operable association with said means for transmitting motion to said alternate action mechanism having an at-rest position and being movable relative to said shell means upon actuation of said push button housing means, and further characterized when in its at-rest position as being configured, arranged and disposed so as not to interfere substantially with light projected from lamps in any one individual shell means through the individual pellucid cover means onto said screen means;
- F. Whereby light emanating from said individual lamps located in said individual shells in said lamp holder means may be projected to an appreciable portion of said upper screen on said push button means.
23. For a lighted push button switch mechanism wherein the switch means are spaced from the point of actuation, a unitary push button and lamp holder actuation means comprising:
- A. Lamp holder base means having a plurality of apertures therein and at least some of said apertures being operable to receive lamp means therein;
- B. Shell means associated with said base means and individually surrounding each of said some apertures receiving said lamp means and projecting thereabove;
- C. Pellucid cover means for each of said shell means and mounted thereon;
- D. Push button housing means telescopingly mounted to said lamp holder base means for relative movement thereto and having an upper screen surface and depending side walls;
- E. Means associated with said side walls of said push button housing means spaced from said screen surface, for operable association with means for transmitting actuating reciprocatory motion past said lamp holder means;
- F. Said means associated with said side walls for operable association with said means for transmitting motion having an at-rest position and being movable upon actuation of said push button housing means and being further characterized when in its at-rest position as being configured, arranged and disposed

- so as not to interfere substantially with light projected from lamps in any one individual shell means through the individual pellucid cover means onto said screen means;
- G. Whereby light emanating from said individual lamps located in said individual shells in said lamp holder means may be projected to an appreciable portion of said upper screen on said push button means.
- 10 24. For a lighted push button switch mechanism wherein the switch means are spaced from the point of actuation, a unitary push button and lamp holder actuation means comprising:
- A. Rectilinear lamp holder base means having a plurality of apertures therein and at least some of said apertures being operable to receive lamp means therein;
- B. A plurality of shell means associated with the corners of said base means and individually surrounding each of said some apertures receiving said lamp means and projecting thereabove, said shell means being further characterized as providing a light reflective surface to reflect light from said lamp means when disposed in said some aperture means;
- C. Said individual shell means being further characterized as projecting from said base means a variable dimension as measured around the periphery thereof to provide a top shell surface angularly disposed with respect to said base means;
- D. Pellucid cover means mounted on the top surface of each of said shell means;
- E. Rectilinear push button housing means telescopingly mounted to said lamp holder base means for relative movement thereto and having an upper screen surface and depending side walls;
- F. Means associated with said push button housing means for operable association with means for transmitting motion to switch means;
- G. Said means associated with said push button housing means for operable association with said means for transmitting motion having an at-rest position and being movable upon actuation of said push button housing means and being further characterized when in its at-rest position as being configured, arranged and disposed so as not to interfere substantially with light projected from lamps in any one individual shell means through the individual pellucid cover means onto said screen means;
- H. Whereby light emanating from said individual lamps located in said individual shells in said lamp holder means may be projected to an appreciable portion of said upper screen on said push button means.
